(57) **ABSTRACT**

A trench box assembly including a trench box and an end cap assembly extending outwardly beyond an end of the trench box. The trench box has two metal plates and spreader bars extending between the plates. The end cap assembly includes a housing and an attachment mechanism. The housing has a first side wall, a second side wall, a top wall, and a back wall which bound and define an interior chamber of a size suitable to receive at least part of a worker's body therein. The attachment mechanism includes attachment hooks which adjustably engage the housing to the spreader bars. When the trench box assembly is installed within a trench the end cap assembly protects a worker performing a task proximate one end of the trench box from being injured by debris falling into a region of the trench adjacent the end of the trench box.

END CAP ASSEMBLY FOR A TRENCH BOX AND METHOD OF UTILIZATION THEREOF

TECHNICAL FIELD

This disclosure is directed to equipment used during excavation operations. More particularly, the disclosure is directed to trench boxes which are installed in trenches during excavation operations. Specifically, the disclosure relates to a trench box end cap assembly which is installed on spreader bars at one end of the trench box and extends outwardly beyond the end of the trench box to protect a worker who is working at one end of the trench.

BACKGROUND ART

In order to construct buildings and install utilities it is frequently necessary to excavate earth at a job site. The excavation may be accomplished by using a wide range of digging tools from shovels to backhoes and through to large excavators which remove rocks and soil from particular areas and deposit them elsewhere. In order to lay utilities or repair utilities it may be necessary to dig a trench, i.e., a hole that is usually deeper than it is wide. If the trench is dug to a depth of four or more feet, then workers entering the trench are at risk of the sides of the trench suddenly collapsing in on them and burying them.

In order to mitigate this risk, it is common for a trench box to be installed in trenches of a certain depth during excavation. In some jurisdictions for example, a trench of five feet or more in depth must have a trench box installed as the trench is excavated. A trench box essentially comprises two or more large metal plates arranged parallel to one another, and separated from one another by spreader bars. Trench boxes are large and heavy and therefore have to be assembled, manipulated, installed, and removed by mechanized lifting equipment. An initial hole is dug by the digging equipment and then the trench box is installed in such a way that the metal plates are located adjacent to the sides of the trench and the spreader bars extend between the metal plates. The spreader bars hold the metal plates a set distance apart from one another. The scoop of the digging equipment is inserted between the two plates and is used to continue to remove rocks and soil in order to extend the length and/or depth of the trench. The trench box is periodically tamped down using the digging equipment and digging is continued until the desired length and depth of the trench is reached. In some instances, additional trench boxes are installed one or both of on top of the first trench box or extend outwardly beyond one end of the first trench box. In some instances, a metal end plate is oriented at right angles to the two metal side plates and is installed between the side plates at an end of the trench box. In other instances, the ends of the trench box are left open and are not covered by an end plate. Once the desired depth and length of trench is dug, soil is backfilled between the sides of the trench and the exterior surfaces of the two metal side plates. The workers can then safely enter into a space defined between the interior surfaces of the metal side plates of the trench box and safely perform their required work.

One of the issues that is encountered while workers are working within the space defined by the trench box is that open ends of the trench box may allow loose rocks and/or soil to fall into that part of the space proximate the open end

of the trench box. Consequently, workers may remain at risk of becoming injured or trapped within the end regions of the trench box.

SUMMARY OF THE INVENTION

In one aspect, an exemplary embodiment of the present disclosure may provide an end cap assembly to a trench box to protect a worker from falling debris, said end cap assembly comprising a housing of a size suitable to receive a part of the worker's body therein; an attachment mechanism operably engaged with the housing; and wherein the attachment mechanism is configured to detachably engage the housing to at least one of a plurality of spreader bars of a trench box.

In one embodiment, the housing may comprise a first side wall and a second side wall located opposite one another; a top wall extending between a top end of the first side wall and a top end of the second side wall; a back wall extending downwardly from the top wall and extending between the first side wall and second side wall; and wherein the first side wall, the second side wall, the top wall, and the back wall bound and define an interior chamber which is sized to receive the part of the worker's body therein. In one embodiment, the end cap assembly may further comprise a first opening to the interior chamber defined between a first end of the first side wall and a first end of the second side wall. In one embodiment, the end cap assembly may further comprise a second opening to the interior chamber defined between a bottom end of the first side wall and a bottom end of the second side wall. In one embodiment, the top wall of the housing may slope downwardly and rearwardly towards a top end of the back wall. In one embodiment, the top wall may be convex in shape. In one embodiment, the attachment mechanism may comprise an attachment hook extending outwardly from the housing; wherein the attachment hook is configured to detachably engage the at least one of the plurality of spreader bars of the trench box. In one embodiment, the attachment hook may be adjustably engaged with the housing. In one embodiment, the attachment mechanism may further comprise a channel defined in the housing; and a fastener extending through a portion of the attachment hook and into the channel; wherein the fastener is selectively movable along the channel to adjust a position of the attachment hook relative to the housing.

In another aspect, an exemplary embodiment of the present disclosure may provide a trench box assembly for protecting a worker from falling debris, said trench box assembly comprising a trench box having a first end and a second end, said trench box comprising a first metal plate and a second metal plate arranged parallel to one another and laterally spaced apart from one another; a plurality of spreader bars extending between the first metal plate and the second metal plate; and an end cap assembly detachably operatively engaged with the plurality of spreader bars of the trench box such that the end cap assembly extends outwardly beyond the first end of the trench box.

In one embodiment, the end cap assembly may include a top wall and wherein the top wall is configured to prevent debris from falling onto a worker working below the top wall. In one embodiment, the end cap assembly may comprise a housing defining an interior chamber of a size suitable to receive at least part of the worker's body therein; an attachment mechanism operably engaged with the housing; wherein the attachment mechanism is configured to detachably engage the end cap assembly with the at least one of the plurality of spreader bars of the trench box. In one

embodiment, the housing may comprise a first side wall and a second side wall located opposite one another; a top wall extending between a top end of the first side wall and a top end of the second side wall; a back wall extending downwardly from the top wall and extending between the first side wall and second side wall; and wherein the first side wall, the second side wall, the top wall, and the back wall bound and define an interior chamber which is sized to receive the part of the worker's body therein. In one embodiment, the attachment mechanism may comprise an attachment hook extending outwardly from the housing; and wherein the attachment hook is configured to detachably engage the at least one of the plurality of spreader bars of the trench box. In one embodiment, the attachment hook may be adjustably engaged with the housing. In one embodiment, the attachment mechanism may further comprise a channel defined in the housing; and a fastener extending through a portion of the attachment hook and into the channel; wherein the fastener is selectively movable along the channel to adjust a position of the attachment hook relative to the housing.

In another aspect, and exemplary embodiment of the present disclosure may provide a method of protecting a worker in a trench from falling debris, wherein the method comprises digging the trench to perform a work operation therein; providing a trench box including a first metal plate and a second metal plate arranged parallel to and laterally spaced apart from one another; providing a plurality of spreader bars extending laterally between the first metal plate and the second metal plate; engaging an end cap assembly with the trench box such that the end cap assembly projects outwardly beyond a first end of the trench box; installing the trench box within the trench; and protecting the worker within the end cap assembly when the worker enters an area of the trench below the end cap assembly.

In one embodiment, the method may further comprise providing a sloped top wall on the end cap assembly; angling the sloped top wall downwardly away from the plurality of spreader bars and the first end of the trench box; and causing debris falling on the sloped top wall to slide off the sloped top wall in a direction moving away from a safe space defined between the first metal plate and the second metal plate of the trench box. In one embodiment, the method may further comprise defining an interior chamber in a housing of the end cap assembly; and allowing a worker to at least partially enter the interior chamber; and preventing debris falling onto the housing from contacting the worker. In one embodiment, providing the plurality of spreader bars may include providing a first set of spreader bars extending laterally between the first metal plate and the second metal plate proximate the first end of the trench box, and providing a second set of spreader bars extending laterally between the first metal plate and the second metal plate proximate a second end of the trench box; and wherein the method further comprises engaging the end cap assembly with the first set of spreader bars such that the end cap assembly projects outwardly beyond the first end of the trench box; and engaging a second end cap assembly with the second set of spreader bars such that the second end cap assembly projects outwardly beyond the second end of the trench box.

BRIEF DESCRIPTION OF THE DRAWINGS

Sample embodiments of the present disclosure are set forth in the following description, are shown in the drawings and are particularly and distinctly pointed out and set forth in the appended claims.

FIG. 1 (FIG. 1) is partial top, front, left side isometric perspective view of a trench box assembly in accordance with the present disclosure partially installed within a trench, with some of the ground around the trench box assembly and a portion of the trench box assembly removed for clarity of illustration.

FIG. 2 (FIG. 2) is a top plan view of the trench box in accordance with the present disclosure shown fully installed within the trench.

10 FIG. 3 (FIG. 3) is a top, front, left side isometric perspective view of an end cap assembly of the trench box assembly of FIG. 1, wherein the end cap assembly is shown in isolation.

15 FIG. 3A (FIG. 3A) is a cross-section of the end cap assembly taken along and looking in the direction of line 3A-3A of FIG. 3.

FIG. 3B (FIG. 3B) is a cross-section of the end cap assembly taken along and looking in the direction of line 3B-3B of FIG. 3.

20 FIG. 4 (FIG. 4) is a partial exploded top, front, left side isometric perspective view of the end cap assembly of FIG. 3, wherein a housing, two attachment bars each having two attachment hooks thereof are shown.

25 FIG. 5 (FIG. 5) is a partial view of one of the attachment bars and the one of the attachment hooks and showing, in phantom, the attachment hook in an alternative adjusted position.

FIG. 6 (FIG. 6) is a cross-section of the attachment bar and the attachment hook of the end cap assembly taken 30 along and looking in the direction of line 6-6 of FIG. 5.

35 FIG. 7 (FIG. 7) is an operational view of a worker utilizing the trench box assembly within the trench, with some of the ground around the trench box assembly and a portion of the trench box assembly removed for clarity of illustration.

40 FIG. 8 (FIG. 8) is a top, front, left side isometric perspective view of a second embodiment of an end cap assembly of the trench box assembly according to an aspect of the present disclosure, wherein the second embodiment of the end cap assembly is shown in isolation.

FIG. 9 (FIG. 9) is an exploded top, back, right side isometric perspective view of the second embodiment of an end cap assembly of FIG. 8, wherein a housing, two attachment bars each having two attachment hooks thereof are shown.

45 Similar numbers refer to similar parts throughout the drawings.

DETAILED DESCRIPTION

50 Referring to FIGS. 1 and 2, there is shown a trench box assembly in accordance with the present disclosure, generally indicated at 10. Trench box assembly 10 generally includes a trench box 20 and an end cap assembly 40. Trench box assembly 10 is installed in a trench "T" dug in the earth, where the trench "T" is bounded and defined by a first trench wall "TW1", a second trench wall "TW2", a third trench wall "TW3" and a fourth trench wall "TW4."

55 Trench box 20 comprises a first metal plate 22, a second metal plate 24, and a plurality of spreader bars 26, 28. During installation within trench "T", first metal plate 22 is positioned adjacent to the first trench wall "TW1" and the second metal plate 24 is positioned adjacent to the third trench wall "TW3". In one specific embodiment, trench box 20 may comprise a first set of spreader bars 26 and a second plurality of spreader bars 28. The first metal plate 22 and the second metal plate 24 are installed within trench "T" parallel

to one another and parallel to a longitudinal axis "X1". First metal plate 22 and second metal plate 24 are spaced a lateral distance apart from one another. The first set of spreader bars 26 and the second set of spreader bars 28 are installed between first metal plate 22 and second metal plate so as to be parallel to one another and parallel to axis "Y1". First set of spreader bars 26 and second set of spreader bars are spaced a distance longitudinally apart from one other. The first set of spreader bars 26 is integrally engaged with the first metal plate 22 and the second metal plate 24 and extends between a first end region 22a of the first metal plate 22 and a first end 24a of the second metal plate 24. The second set of spreader bars 28 is integrally engaged with the first metal plate 22 and the second metal plate 24 and extends between a second end region 22b of the first metal plate 22 and a second end 24b of the second metal plate 24. A safe workspace 23 (FIG. 2) for a worker is defined between an interior surface of first metal plate 22 and an interior surface of second metal plate 24.

Referring to FIGS. 1-3, in accordance with an aspect of the present disclosure, the trench box assembly 10 further comprises at least one end cap assembly 40 operatively engaged with trench box 20. End cap assembly 40 may be operatively engaged with and extend outwardly from either of the first end region 22a, 24a or the second end region 22b, 24b of trench box 20. End cap assembly 40 will be described in greater detail hereafter. FIGS. 1 and 2 show that the trench box assembly 10 includes a first end cap assembly 40A operatively engaged with and extending outwardly from the first end region 22a, 24a of trench box 20 and a second end cap assembly 40B operatively engaged with and extending outwardly from the second end region 22b, 24b of trench box 20. (It will be understood that in other embodiments only a single end cap assembly 40 may be engaged with trench box 20.) The end cap 40, first end cap assembly 40A (FIGS. 1 and 2), and second end cap assembly 40B are identical in all respects to structure and function. It should be therefore understood that the following description of the end cap assembly 40 applies equally to the first end cap assembly 40A and the second end cap assembly 40B illustrated in FIGS. 1 and 2.

End cap assembly 40 includes a housing 50 and an attachment mechanism 70. Housing 50 comprises a frame 52, a first side wall 54, a second side wall 56, a top wall 58, and a back wall 60. The frame 52 may have any number of frame members arranged to adequately support metal plates which make up first side wall 54, second side wall 56, top wall 58, and back wall 60. Referring to FIGS. 3, 3A and 3B, first side wall 54, second side wall 56, top wall 58, and back wall 60 are secured to frame 52 and to one another in any suitable manner such as by welding the components to one another to form an integral structure or by utilizing any suitable type of fastener such as nuts and bolts.

First side wall 54 has a top end 54a, a bottom end 54b, a first end 54c, and a second end 54d. Second side wall 56 has a top end 56a, a bottom end 56b, a first end 56c, and a second end 56d. Each of the first side wall 54 and second side wall 56 is trapezoidal in shape with first end 54c, 56c and second end 54d, 56d being arranged parallel to one another and bottom end 54b, 56b arranged at ninety degrees to first end 54c, 56c and second ends 54d, 56d. As best seen in FIG. 3, first ends 54c, 56c are of a greater length than the associated second end (such as second end 54d) of first side wall 54 and second side wall 56. Top wall 58 has a first end 58a, a second end 58b, a first side 58c, and a second side 58d. Back wall 60 has a top end 60a (FIG. 7) and a bottom end 60b

extending between a first side and a second side. The first side and second side of back wall 60 are not numbered herein.

First side wall 54 and second side wall 56 are arranged parallel to one another and disposed opposite each other about frame 52 of housing 50. First side wall 54 and second side wall 56 are spaced a distance laterally apart from one another other along axis "Y2". Top wall 58 and back wall 60 extend between first side wall 54 and second side wall 56. 10 First end 58a of top wall 58 is aligned with first end 54c of first side wall 54 and first end 56c of second side wall 56. Second end 58b of top wall 58 is aligned with second end 54d of first side wall 54 and the second end of second side wall 56. First side 58c of top wall 58 abuts top end 54a of first side wall 54 and second side 58d of top wall 68 abuts top end 56a of second side wall 56. First side 58c of top wall 58 is welded to frame 52 and to top end 54a of first side wall 54. Second side 58d of top wall 58 is welded to frame 52 and to top end 56a of second side wall 56.

20 Back wall 60 extends between the second ends of the first side wall 54 and second side wall 56. Top end 60a of back wall 60 is welded to frame and to second end 58b of top wall 58. First side 60c of back wall 60 is welded to frame 52 and to second side 54d of first side wall 54. Second side 60d of back wall 60 is welded to frame 52 and to the second side of second side wall 56.

Referring to FIGS. 3 and 4, housing 50 further includes an interior chamber 66 defined and bound by the first side wall 54, the second side wall 56, the top wall 58 and the back wall 60. Housing 50 further comprises a first opening 62 defined between the bottom end 54b of the first side wall 54 and a bottom end 56b of the second side wall 56. Housing 50 further comprises a second opening 64 defined between a first end 54c of the first side wall 54 and a first end 56c of the second side wall 56. The first opening 62 and the second opening 64 are in fluid communication with one another and with the interior chamber 66. The interior chamber 66 defined by housing 50 is of a size suitable to receive at least a part of the worker's body "W". The worker is able to enter interior chamber 66 through one or both of first opening 62 and second opening 64.

Referring to FIGS. 3-4, because of the trapezoidal shape of first side wall 54 and second side wall 56, top wall 58 is sloped and is not parallel to bottom ends 54b, 60b, 56b of first side wall 54, back wall 60, and second side wall 56. In particular, the top wall 58 angles downwardly moving in a direction way from a front 50A of the housing 50 towards a back 50B thereof. Because of this slope, the second end 58b of top wall 58 is closer to the bottom end 54a of the first side wall 54 and to the bottom end 56a of the second side wall 56 than is first end 58a of top wall 58. The downward and rearward slope of top wall 58 is advantageous because when housing 50 is engaged with spreader bars 26 or 28 of trench box 20, as will be discussed later herein, any loose rocks or other debris falling onto top wall 58 will slide down top wall 58 in a direction moving away from the space 23 (FIG. 2) between the first metal plate 22 and second metal plate 24 of trench box 20.

While top wall 58 has been described above as being sloped, it will be understood that the top wall 58 can be of any configuration with respect to the first side wall 54, the second side wall 56 and the back wall 60 which allows for at least a portion of a body "B" of a worker "W" to be within the interior chamber 66.

65 In one specific embodiment, top wall 58 is substantially planar and has no curvature thereto. Top wall 58 allows for dirt or debris "D" (FIG. 7) to come to rest on top the top wall

58 and not enter the interior chamber 66 of the housing 50. In another specific embodiment, the surface of the top wall 58 may be of any shape that allows for dirt or debris "D" (FIG. 7) to not enter the interior chamber 66 of the housing 50.

Referring to FIGS. 3-6 and as discussed earlier herein, end cap assembly 40 further includes attachment mechanism 70 which is adapted to detachably engage the housing 50 to one of the sets of spreader bars 26, 28 of trench box 20. Attachment mechanism 70 comprises at least one attachment bar 80 and at least one attachment hook 100. In one specific embodiment, the end cap assembly 40 includes a first attachment bar 80A and a second attachment bar 80B identical in all respects to one another. It should be therefore understood that the following description of the attachment bar 80 applies equally to the first attachment bar 80A and the second attachment bar 80B. It will be further understood that in other embodiments the end cap assembly 40 may comprise any desired number of attachment bars 80.

The attachment bar 80 is an elongate member which is secured to one of the frame members of frame 52 of housing 50. As illustrated herein attachment bar 80 is a hollow member which is generally square in cross-section. This is best seen in FIG. 6. Attachment bar 80 comprises a front wall 82 and a back wall 84 opposite to one another. The attachment bar 80 further comprises a first wall 86 and a second wall 88 opposite to one another which extend between and are perpendicular to the front wall 82 and the back wall 84. The attachment bar 80 further comprises a top end 90 and a bottom end 92 opposite to one another and perpendicular to the front wall 82, the back wall 84, the first wall 86, and the second wall 88. The attachment bar 80 defines a channel 94 in front wall 82. Channel 94 is oriented generally parallel to first wall 86 and second wall 88 and extends between top end 90 and bottom end 92. The interior surfaces of front wall 82, back wall 84, first wall 86, and second wall 88 define a hollow interior 96. The channel 94 is in fluid communication with the hollow interior 96 (FIG. 6).

Referring now to FIG. 3, each attachment bar 80A, 80B is secured to the housing 50 of the end cap assembly 40. More specifically, the attachment bar 80A is welded or otherwise secured to frame 52 proximate first end 54c of first side wall 54. Attachment bar 80B is welded or otherwise secured to frame 52 proximate first end 56c of second side wall 56. In particular, back wall 84 of each attachment bar 80A, 80B is secured to frame 52, and front wall 82 thereof faces outwardly away from frame 52.

Referring to FIGS. 3-6 and as discussed earlier herein, the attachment mechanism 70 includes at least one attachment hook 100. In one specific embodiment, the attachment mechanism 70 includes a first attachment hook 100A and a second attachment hook 100B which are selectively engaged with the first attachment bar 80A; and a third attachment hook 100C and a fourth attachment hook 100D which are selectively engaged with the second attachment bar 80B. It will be further understood that in other embodiments the attachment mechanism 70 may comprise any number of attachment hooks 100.

All of the attachment hooks 100A, 100B, 100C, and 100D are identical to one another. It should be therefore understood that the following description of the attachment hook 100 applies equally to the first attachment hook 100A, the second attachment hook 100B, the third attachment hook 100C, and the fourth attachment hook 100D.

Referring to FIGS. 5-6, attachment hook 100 comprises a bracket 110 and a hook member 112B integral to and

extending outwardly from the bracket 110. Bracket 110 is configured to receive the attachment bar 80. Bracket 110 comprises a first section 112 and a second section 114 continuous with and substantially perpendicular to one another as shown in FIG. 6. Bracket 110 further comprises a third section 116 continuous with and perpendicular to the second section 114 and substantially parallel to the first section 112. A recess 117 is defined between an interior surface of first section 112, an interior surface of second section 114, and an interior surface of third section 116. The recess 117 is configured to receive a portion of the attachment bar 80 therein. When bar 80 is received in recess 117, an interior surface of the first section 112 is adjacent to a portion of the first wall 86 of the attachment bar 80, an interior surface of the second section 114 is adjacent to the front wall 82 of the attachment bar 80, and an interior surface of the third section 116 is adjacent to a portion of the second wall 88 of the attachment bar 80. Bracket 110 is secured to the attachment bar 80 by way of one or more fasteners 120. In one embodiment, the fasteners 120 comprise bolts 120 which are each inserted through an aperture (not shown) defined in second section 114 of bracket 110. The apertures defined in second section 114 are configured to align with channel 94 in attachment bar 80 when attachment bar 80 and bracket 110 are operably engaged with one another. The shaft of fastener 120 is inserted through the aperture in bracket 110, through the channel 94, and a locknut 124 is engaged therewith to secure the fastener 120 in place. The fastener 120 is able to be rotated in a first direction relative to locknut 124 to loosen fastener 120 so as to allow the position of attachment hook 100 to be adjusted relative to the length of the attachment bar 80 as indicated by arrow "A" (FIG. 5). When attachment hook 100 is at the desired location relative to attachment bar 80, fastener 120 is retightened and thereby locks the attachment hook 100 at the new location on attachment bar 80 (FIG. 5). The ability for the attachment hook 100 to be repositioned along the attachment bar 80 allows for the attachment mechanism 70 to be positioned in various ways to accommodate different spacings of the plurality of spreader bars 26, 28 on the trench box 20.

As illustrated by way of example only, FIG. 3 shows the first attachment hook 100A is secured to the first attachment bar 80A closer to the bottom end 92 thereof than to the top end 90 (FIG. 6). The second attachment hook 100B is secured to the first attachment bar 80A closer to the top end 90 thereof than to the bottom end 92. The third attachment hook 100C is secured to the second attachment bar 80B closer to the bottom end 92 thereof than the top end 90. The fourth attachment hook 100D is secured to the second attachment bar 80B closer to the top end 90 thereof than to the bottom end 92 (FIG. 6). Because the first and third attachment hooks 100A, 100C will be engaged with a same spreader bar 26 or 28, first and third attachment hooks 100A, 100C are laterally aligned with one another and are spaced at a first distance away from the top end 90 of the associated attachment bar 80A, 80B. Similarly, because the second and fourth attachment hooks 100B, 100D are to be engaged with a different spreader bar 26 or 28, second and fourth attachment hooks 100B, 100D are laterally aligned with one another and are spaced a second distance away from the top end 90B of the associated attachment bar 80A, 80B.

It will be understood that instead of the attachment mechanism comprising attachment bars 80A, 80B which are welded or otherwise secured to frame 52 of housing 60, in other embodiments, the attachment bars 80A, 80B may be integral components of the frame 50 and comprise the

leading frame members which are welded or otherwise secured to first ends 54c, 56c of first side wall 54 and second side wall 56, respectively. In this instance, the frame members to which first ends 54c, 56c are operatively engaged would define a channel suitable to receive fasteners 120 therein.

Referring now to FIGS. 5 and 6, attachment hook 100 will be further described. As is evident when reviewing these two figures, first section 112 of bracket 110 comprises a plate into which an inverted U-shaped hole 112A is defined. The provision of hole 112A causes a leading region of first section 112 to assume a hook shape. The hook shape of first section 112 is indicated by the reference character 112B. The radius of curvature of the U-shaped hole 112A is such that the attachment hook 100 presents a curved surface with is adapted to be complementary to the exterior circumferential shape of one of the spreader bars 26, 28 (FIG. 1).

End cap assembly 40 is removably selectively engageable with the plurality of spreader bars 26, 28 at one end of trench box 20. Specifically, the attachment mechanism 70 of the end cap assembly 40 is removably engaged with the plurality of spreader bars 26, 28. More specifically, the attachment hook 100 of the attachment mechanism 70 is removably engaged with the plurality of spreader bars 26, 28. Even more specifically, the hook member 112B of attachment hook 100 is removably engaged with the plurality of spreader bars 26, 28. Most specifically, the curved surface defined by hole 112A of the hook member 112B receives one of the plurality of spreader bars 26, 28 therein to engage end cap assembly 40 to spreader bars 26, 28.

Before or after installation of trench box 20 into a trench "T", end cap assembly is selectively engaged with the trench box 20. A foreman at the job site will determine whether or not workmen will be performing tasks towards one of a first end or a second end of the trench box 20. The foreman will then determine if there is any risk of debris possibly collapsing into the first or second end of the trench box 20 near where the workers will be working. If so, the foreman will determine that there is need of an end cap assembly 40 to be engaged with the spreader bars 26 near the first end of the trench box 20 and/or if a second end cap assembly 40 needs to be engaged with the spreader bars 28 near the second end of the trench box 20. If it has been determined that an end cap assembly 40 needs to be engaged with the spreader bars 26, then the specific spreader bars for engagement of end cap assembly 40 will be selected and the distance between the selected spreader bars 26 is measured. The fasteners 120 on attachment assembly 70 of end cap assembly 40 are loosened and the brackets 110 of attachment hook 100A, 100B, 100C, and 100D are adjusted relative to attachment bars 80 (as indicated by arrow "A" of FIG. 5) to a distance complementary to the distance between the selected spreader bars 26. When attachment hooks 100A, 100B, 100C, 100D are in the correct locations on attachment bars 80, the fasteners are retightened to lock attachment hooks 100A through 100D in place.

End cap assembly 40 is then oriented in such a way that attachment assembly 70 is proximate spreader bars 26 and the sloped top wall 58 of housing 50 angles downwardly away from spreader bars 26. End cap assembly 40 is then lowered into trench "T" and is guided into engagement with spreader bars 26. End cap assembly 40 is particularly lowered until a first spreader bar 26A (FIGS. 1 and 7) is received within the holes 112B of attachment hooks 100B and 100D and a second spreader bar 26B is received within the holes 112B of attachment hooks 100A and 100C. When

this occurs, the entire weight of end cap assembly 40 is borne by first and second spreader bars 26A, 26B, and trench box 20.

FIG. 7 shows trench box assembly 10 in operation with end cap assembly 40 engaged with spreader bars 26A, 26B and shows a worker "W" who is working on a pipe "P" under the protection provided by end cap assembly 40. In particular, the sloped top wall 58 of end cap assembly 40 protects the worker "W" from debris "D" falling in a direction indicated by arrow "B" into the trench "T". Although not illustrated herein, it will be understood that first side wall 54 protects the worker "W" from debris falling into the trench off trench wall "TW3"; second side wall 56 protects the worker "W" from debris falling into the trench off trench wall "TW1"; and back wall 60 protects the worker "W" from debris falling into the trench off trench wall "TW4". FIG. 7 shows worker "W" on their knees while working. However, should the worker stand up, he or she will be able to safely do so, and their head and torso will be able to enter into the interior chamber 66 bounded and defined by the walls of housing 50.

It will be understood that it is easy to raise or lower end cap assembly 40 relative to the top (or bottom) of the trench, simply by engaging end cap assembly 40 with different spreader bars other than 26A and 26B. FIG. 1 shows a second end cap assembly 40 engaged with spreader bars 28 at the second end of the trench box 20. In each instance, the end cap assembly 40 projects for a distance outwardly beyond the associate end of the first and second metal plates 22, 24 of trench box 20 and into a portion of the trench "T" which is not protected by metal plates adjacent the side walls "TW1", "TW3".

Referring to FIGS. 1, 2, and 7, the present disclosure furthermore relates to a method of protecting a worker in a trench "T" from falling debris "D". The method includes digging the trench "T" in the ground "G" to perform a work operation therein. The method further comprises providing a first metal plate 22 and a second metal plate 24 (FIG. 2) arranged parallel to one another along axis "X1" with the metal plates 22, 24 laterally spaced apart from one another and supporting opposing side walls of the trench, namely walls "TW1" and "TW3". The method includes providing a plurality of spreader bars 26, 28 extending laterally between the first metal plate 22 and the second metal plate 24 to hold the plates a fixed distance apart from one another and to provide a safe workspace 23 for a worker "W" therebetween. The method comprises engaging an end cap assembly 40 with a trench box 20 such that the end cap assembly 40 projects outwardly beyond one end of the trench box 20, wherein the trench box 20 comprises the first metal plate 22, the second metal plate 24 with ends 22a, 24a and 22b, 24b. The method further comprises defining an interior chamber 66 (FIG. 7) within the end cap assembly 40. The method even further comprises installing the first metal plate 22, and second metal plate 24, the plurality of spreader bars 26, 28 and the end cap assembly 40 within the trench "T". The method additionally comprises protecting the worker "W" with the end cap assembly 40 where the worker "W" is at least partially covered by one or more walls 54, 56, 58, 60 of the housing 50 of end cap assembly 40 and/or at least partially enters the interior chamber 66 defined by the housing 50 of end cap assembly 40.

In one specific embodiment, the disclosed method may further comprise shielding the worker "W" from debris "D" falling into the trench "T" in the direction "B" (FIG. 7) with the end cap assembly 40 and allowing a worker "W" to enter

11

the interior chamber **66** of the end cap assembly **40** and protecting the worker from the debris "D" falling into the trench "T".

The method further comprises providing a first set of spreader bars **26** extending laterally between a first end region **22a** of the first metal plate **22** and a first end region **24a** of the second metal plate **24**. The method may further comprise providing a second set of spreader bars **28** extending laterally between a second end region **22b** of the first metal plate **22** and a second end region **24b** of the second metal plate **24**. The method may comprise engaging a first end cap assembly **40A** (FIG. 2) with the first set of spreader bars **26** such that the first end cap assembly **40A** protects outwardly beyond the first end region **22a** of the first metal plate **22** and the first end region **24a** of the second metal plate **24**. The method may further comprise engaging a second end cap assembly **40B** with the second set of spreader bars **28** such that the end cap assembly **40B** projects outwardly beyond the second end region **22b** of the first metal plate **22** and the second end region **24b** of the second metal plate **24**.

Referring now to FIGS. 8 and 9, there is shown a second embodiment of an end cap assembly in accordance with an aspect of the present disclosure, generally indicated at **1040** (FIG. 9). End cap assembly **1040** comprises a housing **1050** and an attachment assembly **1070** (FIG. 9). End cap assembly **1040** is identical in function and structure to end cap assembly **40** except for particular features which will be discussed hereafter.

Housing **1050** comprises a frame **1052**, a first side wall **1054**, a second side wall **1056**, a top wall **1058**, and a back wall **1060**. The first side wall **1054** and the second side wall **1056** of housing **1050** are arranged parallel to one another and opposite to each other. First side wall **1054** and second side wall **1056** are configured to be substantially identical in structure and function to first side wall **54** and second side wall **56** of end cap assembly **40**. Similarly, back wall **1060** is configured to be substantially identical in structure and function to back wall **60** of end cap assembly **40** except that back wall **1060** has a bottom end **1060b** (FIG. 9) which terminates a short distance vertically upwardly from bottom ends **1054b** and **1056b** of first and second side walls **1054** and **1056**, respectively. Because first side wall **1054**, second side wall **1056** and back wall **1060** are substantially identical to or substantially similar to first side wall **54**, second side wall **56** and back wall **60** of end cap assembly **40**, first and second side walls **1054**, **1056** and back wall **1060** will not be discussed in much detail hereafter.

Housing **1050** differs from housing **50** of end cap assembly **40** with respect to certain features of the frame **1050** and of the top wall **1058**. Frame **1050** is used in a substantially identical manner to frame **50**, i.e., to serve as a base structure to which the first side wall **1054**, second side wall **1056**, top wall **1058**, and back wall **1060** are fixedly engaged by welding or by use of suitable fastener mechanisms. Frame **1050** differs from frame **50** in that frame **1050** includes one or more support rods **1069** which extend between a first frame member **1052A** and a second frame member **1052B**. First frame member **1052A** is a region of the frame **1052** to which a first end **1054c** of first side wall **1054** is secured. Second frame member **1052B** is a region of frame **1052** to which a first end **1056c** of second side wall **1056** is secured. The one or more support rods **1069** extend between first frame member **1052A** and second frame member **1052B** in a location proximate to top wall. Support rods **1069** add structural integrity and strength to frame **1052**. First and second frame members **1052A**, **1052B** and support rods

12

1069 bound and define a first opening **1062** (FIG. 8) which is in fluid communication with an interior chamber **1066** defined by the frame **1052**, first side wall **1054**, second side wall **1056**, top wall **1058**, and back wall **1060**. A second opening **1064** to interior chamber **1066** is defined by the lower frame members of frame **1052** and the bottom ends **1054b**, **1056b**, of first and second side walls **1054**, **1056**, and the bottom end **1060b** (FIG. 9) of back wall **1060**.

As with end cap assembly **40**, in end cap assembly **1040** an attachment mechanism **1070** is engaged with housing **1050** to enable end cap assembly **1040** to be engaged with spreader bars **26**, **28** of a trench box assembly **10**. FIG. 9 shows that attachment mechanism **1070** comprises a pair of attachment bars **1080** (FIG. 9) and a plurality of attachment hooks **1100**. The attachment mechanism **1070** is identical in structure and function to attachment mechanism **70** and therefore will not be discussed in any further detail herein, other than to indicate that the attachment bars **1080** are secured to first frame member **1052A** and second frame member **1052B** via welding or any other suitable fastener assembly. As will be evident from the fact that all of the components of end cap assembly are fabricated from metal, the welding or other suitable fastener assembly used to secure attachment mechanism **70** to housing **1050** must be strong enough to enable the entire weight of end cap assembly **40** to be supported by spreader bars **26**, **28** and first and second metal plates **22**, **24**. This holds true for end cap assembly **1040** and end cap assembly **40**.

As indicated earlier herein, top wall **1058** of end cap assembly **1040** differs from top wall **58** of end cap assembly **40**. The function of top wall **1058** is substantially identical to the function of top wall **58** but the structure of top wall **1058** differs from that of top wall **58**. Top wall **1058** has a first end **1058a**, a second end **1058b**, a first side **1058c**, and a second side **1058d**. When top wall **1058** is viewed from one end and looking towards back wall **1060** as in FIG. 9, top wall **1058** is arcuate in shape. In particular, top wall **1058** is convex in shape with the zenith of the convex shape, i.e., the highest point thereof, being located along a longitudinal midline of the top wall **1058**. The longitudinal midline runs parallel to first side **1058c** and second side **1058d** and is located midway between first side **1058c** and second side **1058d**. The top wall **1058** slopes gently downwardly from the longitudinal midline to each of the first side **1058c** and the second side **1058d**. The curvature of top wall **1058** is substantially constant from first end **1058a** to second end **1058b** of top wall **1058**.

Top wall **1058** is slanted where a second end **1058b** (FIG. 9) is closer to the bottom end **1054b** of the first side wall **1054** and the bottom end **1056b** of the second side wall **1056** than first end **1058a** (FIG. 9). It should be understood that the top wall **1058** can be of any configuration with respect to the first side wall **1054**, the second side wall **1056** and the back wall **1060** where the top wall **1058** allows for a portion of a body "B" of a worker "W" to be within the interior chamber **1066**. In addition to being convexly surface, top wall **1058** slopes downwardly moving in a direction away from first end **1058a** thereof and towards the second end **1058b** thereof. Like in top wall **58** of end cap assembly **40**, the degree of slope imparted to top wall **1058** is dictated by the angle of top ends **1054a**, **1056a** of side walls **1054**, **1056**.

Top wall is suitably secured to frame **1052** to cover the gap between top end **1054a** of first side wall **1054** and top end **1056a** (FIG. 9) of second side wall **1056**. As shown in FIG. 9, top wall **1058** may not extend all of the distance along the top ends **1054a**, **1056a** of first and second side walls **1054**, **1056** from first ends **1054c**, **1056c** to second

ends **1054d**, **1056d** thereof, but may, instead originate a short distance inwardly from first ends **1054c**, **1056c** and terminate a short distance inwardly from second ends **1054d**, **1056d**. A gap **1068** may therefore be defined between second end **1058b** of top wall **1058** and top end **1060a** of back wall **1060**.

End cap assembly **1040** is secured to spreader bars **26**, **28** in a substantially identical manner to how end cap assembly **40** is secured to spreader bars **26**, **28**. End cap assembly **1040** is secured to spreader bars **26** or **28** so that end cap assembly **1040** projects outwardly for a distance beyond the first end regions **22a**, **24a** of metal plates **22**, **24** of trench box **20** or projects outwardly for a distance beyond the second end regions **22b**, **24b** of metal plates **22**, **24** as desired. End cap assembly **1040** will protect a worker "W" (FIG. 7) in a substantially identical manner to end cap assembly **40**. The combination of the curvature of top wall **1058** and the slope thereof, may serve to better direct any debris falling on top wall **1058** in a direction away from the safe workspace **23** defined between the metal plates **22**, **24** of trench box **20**.

In one specific embodiment, a surface of the top wall **58** is concavely curved with respect to the bottom end **1054b** of the first side wall **1054** and the bottom end **1056b** of the second side wall **1056**. Further in this embodiment, the surface of the top wall **1058** allows for dirt or debris "D" (FIG. 7) to fall off the top wall **1058** and not enter the interior chamber **1066** of the housing **1050**. In another specific embodiment, the surface of the top wall **1058** may be of any shape that allows for dirt or debris "D" (FIG. 7) to not enter the interior chamber **1066** of the housing **1050**.

A method of protecting a worker "W" in a trench "T" from falling debris "D" (FIG. 7) in accordance with the present disclosure includes digging the trench "T" to perform a work operation therein; providing a trench box assembly **10** including trench box **20** and an end cap assembly **40** or **1040**. The trench box **20** comprises a first metal plate **22** and a second metal plate **24** arranged parallel to and laterally spaced apart from one another. The method further includes providing a plurality of spreader bars **26**, **28** extending laterally between the first metal plate **22** and the second metal plate **24**; engaging the end cap assembly **40** (or **1040**) with the spreader bars **26**, **28** such that the end cap assembly **40** or **1040** projects outwardly beyond a first end **22a**, **24a** of the trench box **20**; installing the trench box assembly **10** within the trench "T"; and protecting the worker "W" with the end cap assembly **40** or **1040** when the worker enters an area of the trench "T" below the end cap assembly **40** or **1040**.

The method may further comprise providing a sloped top wall **58** or **1058** on the end cap assembly **40** or **1040**, respectively; angling the sloped top wall **58** or **1058** downwardly away from the plurality of spreader bars **26**, **28** and the first end **22a**, **24a** of the trench box **20**; and causing debris "D" falling on the sloped top wall **58** or **1058** to slide off the sloped top wall in a direction moving away from a safe space **23** defined between the first metal plate **22** and the second metal plate **24** of the trench box **20**. The method further comprises defining an interior chamber **66** or **1066** in a housing **50** or **1050** of the end cap assembly **40** or **1040**, respectively; and allowing a worker "W" to at least partially enter the interior chamber **66** or **1066**; and preventing debris "D" falling onto the housing **50** or **1050** from contacting the worker "W". Providing the plurality of spreader bars may include providing a first set of spreader bars **26** extending laterally between the first metal plate **22** and the second metal plate **24** proximate the first end **22a**, **24a** of the trench box **20**, and providing a second set of spreader bars **28**

extending laterally between the first metal plate **22** and the second metal plate **24** proximate a second end **22b**, **24b** of the trench box **20**; and wherein the method further comprises engaging the end cap assembly **40**, **40A**, or **1040** with the first set of spreader bars **26** such that the end cap assembly **40**, **40A**, or **1040** projects outwardly beyond the first end **22a**, **24a** of the trench box **20**; and engaging a second end cap assembly **40**, **40B**, or **1040** with the second set of spreader bars **28** such that the second end cap assembly **40**, **40B**, or **1040** projects outwardly beyond the second end **22b**, **24b** of the trench box **20**. Obviously, a worker "W" working proximate the first end **22a**, **24a** of trench box **20** will be protected by end cap assembly **40**, **40A**, or **1040** and a worker "W" working proximate second end **22b**, **24b** of trench box **20** will be protected by end cap assembly **40**, **40B**, or **1040**.

It will be further understood that any connections between various components not explicitly described herein may be made through any suitable means including mechanical fasteners, or more permanent attachment means, such as welding or the like. Alternatively, where feasible and/or desirable, various components of the present disclosure may be integrally formed as a single unit.

Unless explicitly stated that a particular shape or configuration of a component is mandatory, any of the elements, components, or structures discussed herein may take the form of any shape. Thus, although the figures depict the various elements, components, or structures of the present disclosure according to one or more exemplary embodiments, it is to be understood that any other geometric configuration of that element, component, or structure is entirely possible.

Various inventive concepts may be embodied as one or more methods, of which an example has been provided. The acts performed as part of the method may be ordered in any suitable way. Accordingly, embodiments may be constructed in which acts are performed in an order different than illustrated, which may include performing some acts simultaneously, even though shown as sequential acts in illustrative embodiments.

While various inventive embodiments have been described and illustrated herein, those of ordinary skill in the art will readily envision a variety of other means and/or structures for performing the function and/or obtaining the results and/or one or more of the advantages described herein, and each of such variations and/or modifications is deemed to be within the scope of the inventive embodiments described herein. More generally, those skilled in the art will readily appreciate that all parameters, dimensions, materials, and configurations described herein are meant to be exemplary and that the actual parameters, dimensions, materials, and/or configurations will depend upon the specific application or applications for which the inventive teachings is/are used. Those skilled in the art will recognize, or be able to ascertain using no more than routine experimentation, many equivalents to the specific inventive embodiments described herein. It is, therefore, to be understood that the foregoing embodiments are presented by way of example only and that, within the scope of the appended claims and equivalents thereto, inventive embodiments may be practiced otherwise than as specifically described and claimed. Inventive embodiments of the present disclosure are directed to each individual feature, system, article, material, kit, and/or method described herein. In addition, any combination of two or more such features, systems, articles, materials, kits, and/or methods, if such features, systems, articles,

15

materials, kits, and/or methods are not mutually inconsistent, is included within the inventive scope of the present disclosure.

All definitions, as defined and used herein, should be understood to control over dictionary definitions, definitions in documents incorporated by reference, and/or ordinary meanings of the defined terms.

The articles “a” and “an,” as used herein in the specification and in the claims, unless clearly indicated to the contrary, should be understood to mean “at least one.” The phrase “and/or,” as used herein in the specification and in the claims (if at all), should be understood to mean “either or both” of the elements so conjoined, i.e., elements that are conjunctively present in some cases and disjunctively present in other cases. Multiple elements listed with “and/or” should be construed in the same fashion, i.e., “one or more” of the elements so conjoined. Other elements may optionally be present other than the elements specifically identified by the “and/or” clause, whether related or unrelated to those elements specifically identified. Thus, as a non-limiting example, a reference to “A and/or B”, when used in conjunction with open-ended language such as “comprising” can refer, in one embodiment, to A only (optionally including elements other than B); in another embodiment, to B only (optionally including elements other than A); in yet another embodiment, to both A and B (optionally including other elements); etc. As used herein in the specification and in the claims, “or” should be understood to have the same meaning as “and/or” as defined above. For example, when separating items in a list, “or” or “and/or” shall be interpreted as being inclusive, i.e., the inclusion of at least one, but also including more than one, of a number or list of elements, and, optionally, additional unlisted items. Only terms clearly indicated to the contrary, such as “only one of” or “exactly one of,” or, when used in the claims, “consisting of,” will refer to the inclusion of exactly one element of a number or list of elements. In general, the term “or” as used herein shall only be interpreted as indicating exclusive alternatives (i.e. “one or the other but not both”) when preceded by terms of exclusivity, such as “either,” “one of,” “only one of,” or “exactly one of.” “Consisting essentially of,” when used in the claims, shall have its ordinary meaning as used in the field of patent law.

As used herein in the specification and in the claims, the phrase “at least one,” in reference to a list of one or more elements, should be understood to mean at least one element selected from any one or more of the elements in the list of elements, but not necessarily including at least one of each and every element specifically listed within the list of elements and not excluding any combinations of elements in the list of elements. This definition also allows that elements may optionally be present other than the elements specifically identified within the list of elements to which the phrase “at least one” refers, whether related or unrelated to those elements specifically identified. Thus, as a non-limiting example, “at least one of A and B” (or, equivalently, “at least one of A or B,” or, equivalently “at least one of A and/or B”) can refer, in one embodiment, to at least one, optionally including more than one, A, with no B present (and optionally including elements other than B); in another embodiment, to at least one, optionally including more than one, B, with no A present (and optionally including elements other than A); in yet another embodiment, to at least one, optionally including more than one, A, and at least one, optionally including more than one, B (and optionally including other elements); etc.

16

While components of the present disclosure are described herein in relation to each other, it is possible for one of the components disclosed herein to include inventive subject matter, if claimed alone or used alone. In keeping with the above example, if the disclosed embodiments teach the features of A and B, then there may be inventive subject matter in the combination of A and B, A alone, or B alone, unless otherwise stated herein.

When a feature or element is herein referred to as being

10 “on” another feature or element, it can be directly on the other feature or element or intervening features and/or elements may also be present. In contrast, when a feature or element is referred to as being “directly on” another feature or element, there are no intervening features or elements present. It will also be understood that, when a feature or element is referred to as being “connected”, “attached” or “coupled” to another feature or element, it can be directly connected, attached or coupled to the other feature or element or intervening features or elements may be present. 15 In contrast, when a feature or element is referred to as being “directly connected”, “directly attached” or “directly coupled” to another feature or element, there are no intervening features or elements present. Although described or shown with respect to one embodiment, the features and 20 elements so described or shown can apply to other embodiments. It will also be appreciated by those of skill in the art that references to a structure or feature that is disposed “adjacent” another feature may have portions that overlap or underlie the adjacent feature.

25 Spatially relative terms, such as “under”, “below”, “lower”, “over”, “upper”, “above”, “behind”, “in front of”, and the like, may be used herein for ease of description to describe one element or feature’s relationship to another element(s) or feature(s) as illustrated in the figures. It will be

30 understood that the spatially relative terms are intended to encompass different orientations of the device in use or operation in addition to the orientation depicted in the figures. For example, if a device in the figures is inverted, elements described as “under” or “beneath” other elements 35 or features would then be oriented “over” the other elements or features. Thus, the exemplary term “under” can encompass both an orientation of over and under. The device may be otherwise oriented (rotated 90 degrees or at other orientations) and the spatially relative descriptors used herein 40 interpreted accordingly. Similarly, the terms “upwardly”, “downwardly”, “vertical”, “horizontal”, “lateral”, “transverse”, “longitudinal”, and the like are used herein for the purpose of explanation only unless specifically indicated otherwise.

45 Although the terms “first” and “second” may be used herein to describe various features/elements, these features/elements should not be limited by these terms, unless the context indicates otherwise. These terms may be used to distinguish one feature/element from another feature/element. 50 Thus, a first feature/element discussed herein could be termed a second feature/element, and similarly, a second feature/element discussed herein could be termed a first feature/element without departing from the teachings of the present invention.

55 An embodiment is an implementation or example of the present disclosure. Reference in the specification to “an embodiment,” “one embodiment,” “some embodiments,” “one particular embodiment,” “an exemplary embodiment,” or “other embodiments,” or the like, means that a particular feature, structure, or characteristic described in connection with the embodiments is included in at least some embodiments, but not necessarily all embodiments, of the invention.

The various appearances "an embodiment," "one embodiment," "some embodiments," "one particular embodiment," "an exemplary embodiment," or "other embodiments," or the like, are not necessarily all referring to the same embodiment.

If this specification states a component, feature, structure, or characteristic "may," "might," or "could" be included, that particular component, feature, structure, or characteristic is not required to be included. If the specification or claim refers to "a" or "an" element, that does not mean there is only one of the element. If the specification or claims refer to "an additional" element, that does not preclude there being more than one of the additional element.

Additionally, the method of performing the present disclosure may occur in a sequence different than those described herein. Accordingly, no sequence of the method should be read as a limitation unless explicitly stated. It is recognizable that performing some of the steps of the method in a different order could achieve a similar result.

In the claims, as well as in the specification above, all transitional phrases such as "comprising," "including," "carrying," "having," "containing," "involving," "holding," "composed of," and the like are to be understood to be open-ended, i.e., to mean including but not limited to. Only the transitional phrases "consisting of" and "consisting essentially of" shall be closed or semi-closed transitional phrases, respectively.

To the extent that the present disclosure has utilized the term "invention" in various titles or sections of this specification, this term was included as required by the formatting requirements of word document submissions pursuant the guidelines/requirements of the United States Patent and Trademark Office and shall not, in any manner, be considered a disavowal of any subject matter.

In the foregoing description, certain terms have been used for brevity, clearness, and understanding. No unnecessary limitations are to be implied therefrom beyond the requirement of the prior art because such terms are used for descriptive purposes and are intended to be broadly construed.

Moreover, the description and illustration of various embodiments of the disclosure are examples and the disclosure is not limited to the exact details shown or described.

What is claimed is:

1. An end cap assembly to a trench box to protect a worker from falling debris, said end cap assembly comprising:
  - a housing of a size suitable to receive a part of a body of the worker therein;
  - the housing comprises:
    - a first side wall and a second side wall located opposite one another;
    - a top wall extending between a top end of the first side wall and a top end of the second side wall;
    - a back wall extending downwardly from the top wall and extending between the first side wall and second side wall;
    - wherein the first side wall, the second side wall, the top wall, and the back wall bound and define an interior chamber which is sized to receive the part of the worker's body therein;
    - an attachment mechanism operably engaged with the housing; and
    - wherein the attachment mechanism is configured to detachably engage the housing to at least one of a plurality of spreader bars of the trench box.

2. The end cap assembly according to claim 1, further comprising a first opening to the interior chamber defined between a first end of the first side wall and a first end of the second side wall.

5 3. The end cap assembly according to claim 2, further comprising a second opening to the interior chamber defined between a bottom end of the first side wall and a bottom end of the second side wall.

10 4. The end cap assembly according to claim 1, wherein the top wall of the housing slopes downwardly and rearwardly towards a top end of the back wall.

15 5. The end cap assembly according to claim 4, wherein the top wall is convex in shape.

15 6. The end cap assembly according to claim 1, wherein the attachment mechanism comprises:

an attachment hook extending outwardly from the housing; and

wherein the attachment hook is configured to detachably engage the at least one of the plurality of spreader bars of the trench box.

7. The end cap assembly according to claim 6, wherein the attachment hook is adjustably engaged with the housing.

20 8. The end cap assembly according to claim 7, wherein the attachment mechanism further comprises:

a channel defined in the attachment mechanism; and a fastener extending through a portion of the attachment hook and into the channel; wherein the fastener is selectively movable along the channel to adjust a position of the attachment hook relative to the housing.

9. A trench box assembly for protecting a worker from falling debris, said trench box assembly comprising:

a trench box having a first end and a second end, said trench box comprising:

a first metal plate and a second metal plate arranged parallel to one another and laterally spaced apart from one another;

a plurality of spreaders bars extending between the first metal plate and the second metal plate;

an end cap assembly detachably operatively engaged with the plurality of spreader bars of the trench box such that the end cap assembly extends outwardly beyond the first end of the trench box; and

wherein the end cap assembly includes a top wall and wherein the top wall is configured to prevent debris from falling onto the worker working below the top wall.

10 10. The trench box assembly according to claim 9, wherein the end cap assembly comprises:

a housing defining an interior chamber of a size suitable to receive at least part of a body of the worker therein; an attachment mechanism operably engaged with the housing; and

wherein the attachment mechanism is configured to detachably engage the end cap assembly with at least one of the plurality of spreader bars of the trench box.

11 11. The trench box assembly according to claim 10, wherein the housing comprises:

a first side wall and a second side wall located opposite one another;

the top wall extending between a top end of the first side wall and a top end of the second side wall;

a back wall extending downwardly from the top wall and extending between the first side wall and second side wall; and

19

wherein the first side wall, the second side wall, the top wall, and the back wall bound and define the interior chamber which is sized to receive the part of the worker's body therein.

12. The trench box assembly according to claim **10**, wherein the attachment mechanism comprises:

an attachment hook extending outwardly from the housing; and

wherein the attachment hook is configured to detachably engage the at least one of the plurality of spreader bars of the trench box.

13. The trench box assembly according to claim **12**, wherein the attachment hook is adjustably engaged with the housing.

14. The trench box assembly according to claim **13**, wherein the attachment mechanism further comprises: a channel defined in the attachment mechanism; and a fastener extending through a portion of the attachment hook and into the channel; wherein the fastener is selectively movable along the channel to adjust a position of the attachment hook relative to the housing.

15. A method of protecting a worker in a trench from falling debris, wherein the method comprises:

digging the trench to perform a work operation therein; providing a trench box including a first metal plate and a second metal plate arranged parallel to and laterally spaced apart from one another;

providing a plurality of spreader bars extending laterally between the first metal plate and the second metal plate; engaging an end cap assembly with the trench box such that the end cap assembly projects outwardly beyond a first end of the trench box;

providing a sloped top wall on the end cap assembly;

20

angling the sloped top wall downwardly away from the plurality of spreader bars and the first end of the trench box;

installing the trench box within the trench;

causing debris falling on the sloped top wall to slide off the sloped top wall in a direction moving away from a safe space defined between the first metal plate and the second metal plate of the trench box; and

protecting the worker within the end cap assembly when the worker enters an area of the trench below the end cap assembly.

16. The method according to claim **15**, further comprising:

defining an interior chamber in a housing of the end cap assembly;

allowing the worker to at least partially enter the interior chamber; and

preventing debris falling onto the housing from contacting the worker.

17. The method according to claim **15**, wherein providing the plurality of spreader bars includes providing a first set of spreader bars extending laterally between the first metal plate and the second metal plate proximate the first end of the trench box, and providing a second set of spreader bars extending laterally between the first metal plate and the second metal plate proximate a second end of the trench box; wherein the method further comprises:

engaging the end cap assembly with the first set of spreader bars such that the end cap assembly projects outwardly beyond the first end of the trench box; and

engaging a second end cap assembly with the second set of spreader bars such that the second end cap assembly projects outwardly beyond the second end of the trench box.
